UNITED STATES PATENT OFFICE.

WILLIAM B. D. PENNIMAN, OF BALTIMORE, MARYLAND.

APPARATUS FOR CRACKING OILS.

Application filed April 25, 1917. Serial No. 164,337.

To all whom it may concern:

Be it known that I, WILLIAM B. D. PENNIMAN, a citizen of the United States of America, residing in the city of Baltimore, 5 State of Maryland, have invented certain new and useful Improvements in Apparatus for Cracking Oils, of which the following is a specification.

Cracking in the sense in which the word 10 is used in this application, is applied to the operation by which the hydrocarbons of high boiling point and correspondingly high molecular weight are broken down by heat into two products, one of which is in general 15 more volatile and the other less volatile than the original material cracked. The object of this invention is to so regulate the conditions under which the cracking operation is carried on that the character of the 20 products and the practical difficulties which ordinarily occur will be entirely or almost entirely avoided. These difficulties are in the main as follows:—1st—formation of undesirable distillation products, i. e., gas, 25 heavier products than gasoline, unsaturated hydrocarbons, or other undesirable products; 2nd—coke in the still, which reduces the efficiency of the heating surfaces, is accompanied generally by the formation of an excessive amount of gas and is eminently undesirable; and 30 3rd—excessive cost of fuel.

Cracking of oils under pressure for the making of commercial gasoline, as ordinarily conducted, is accomplished by heating the still which contains the oil by means 35 of a free flame. Now, the temperature at which the desired cracking operation is effected is so close to the temperature at which an excess coke is formed that unless particular provision is made to secure the necessary high temperature and still avoid the slightly higher temperature which results 40 in the formation of coke, the operation is uneconomical from the standpoint of production and perilous to the operator on account of the danger of explosion. By using 45 the apparatus described in this and my co-pending application, such formation of coke and undesirable products is largely avoided, 50 not only by the regulation of the heat applied to the oil, but other devices which are described in detail. As the fuel used is burned under the superheaters and boiler so constructed that the entire heat value is 55 utilized, great economy of fuel is necessarily secured.

In my U. S. Patents Nos. 766,841, 902, 60 300 and 933,577, I have described various features and combinations of features of an apparatus for heating oil by means of steam, obtaining high temperatures at low pressures. My present application relates to an apparatus for cracking oils in which the patented apparatus may be utilized when combined with other features and apparatus 65 as herein described, it being understood however, that I do not confine the scope of the present invention to the details disclosed in the above patents.

In the present instance I use a series of 70 stills or tanks heated by steam or other fluids, the temperature of the fluid utilized at each still and the thermal conditions in each still, and the pressures in all the stills, being controlled, preferably by automatic means. In 75 the practice of my invention, the hydrocarbon being treated is passed from still to still and treated in each still in turn at the temperature found to be the most favorable for cracking, i. e., the production of the highest 80 percentage of gasoline from the oil in the particular condition in which it arrives at that still. This is on the principle that certain oils are cracked at one temperature and heating the residue at another temperature 85 makes it possible to crack still other oils, and so on until cracking of all available or crackable oils is completed.

As in all cracking under pressure, a considerable amount of oil is vaporized without 90 being cracked, which term is used to indicate that there is change of chemical structure as distinguished from a purely physical change, it is desirable to control the temperature of the vapors and gases. This may be 95 done either for the purpose of condensing the uncracked vapors or for cracking the vaporized oil, or both, that is, by using a plurality of successive temperature controlling members, some for heating and others 100 for cooling the gases and vapors. To this end, I have provided a vapor chamber, passage or stillhead with one or more temperature controlling members, i. e., means for heating or cooling the vapors with means 105 for positively and definitely controlling the heat-exchanging capacity or temperature of said members.

As the quality and constituents of the vapors coming from the different stills when 110 these contain different oils heated at different temperatures, are different, it is found

advisable to have a separate stillhead or vapor chamber for each still and separately controlled temperature regulating means in each stillhead. However, the stillhead arrangement may be varied within the scope of the invention.

One means for controlling the temperature of any of such stillheads or vapor chambers herein referred to is by means of steam supplied at regulated temperatures and low pressures as disclosed in my aforesaid 10 patents. In accordance with my present invention I may however use water instead of wet steam, or within the scope of my 15 broader claims, I may use other heating means and heat controlling means and the term steam is used for convenience to indicate any heat carrying fluid.

In the preferred form, the steam from 20 each stillhead or vapor temperature controlling unit and the steam from each still is continued in the system giving the greatest possible economy and the steam is all utilized. The thermal condition of both the 25 heating units for the stills and the heating or cooling units for the vapor is controlled by connections to superheated and wet steam or corresponding sources, the flow being regulated by my valve apparatus or otherwise, any form of regulation being within 30 the broad scope of my invention.

In the accompanying drawing, I have illustrated an apparatus embodying the various features of my invention, the figure 35 being a diagrammatic elevation in which the parts have as far as possible been shown in a plane parallel to the paper for convenience in illustration.

Referring to the drawing by numerals, I 40 have shown a series of stills or tanks 1, 2, 3 for the oil which may be kerosene or one of the heavier petroleum oils, all of which are known to be made up of mixtures of different hydrocarbons. The tanks or stills 1, 2 45 and 3 are connected together by pipes 4 and 5 to provide for the flow of the oil from one still to the next as hereinafter described and there is an inlet or supply pipe 6 and an outlet 7. Oil is supplied to the pipe 6, flowing 50 into the still 1 and overflowing at 4 whence it passes through the pipe 4 and overflows into the still 2 passing in turn through the still 2 whence it overflows through the pipe 5 into the still 3 and is drawn off by the pipe 55 7 passing by any suitable main 8 to a reservoir or receptacle for residue. The flow may be maintained by a pump. The return or waste main 8, as shown, is provided with connections 9 and 10 to the pipes 4 and 5 60 respectively which connections are controlled by three-way valves 11 and 12 so that the flow may be diverted when desired. In each of the stills 1, 2 and 3, there is a suitable steam coil 13, 14 and 15 or other 65 means for bringing the steam or other suit-

able heat vehicle in heat-exchanging relation with the oil. These coils are connected each to two sources of fluid under different thermal conditions, referred to herein as a source of superheated steam 16 and wet 70 steam 17, or within the broader conception of the invention, other heat regulating means may be used.

Referring to the still 3 which would under ordinary circumstances be heated to the 75 highest temperature because it receives the heaviest oils which have already been treated in stills 1 and 2, the temperature of this coil or the fluid supply to it is controlled by a valve gear indicated at 18 and similar or in 80 a general way equivalent in construction to that shown in my Patent No. 902,600. To this valve gear, superheated steam or other fluid at a correspondingly high temperature, is led by way of a pipe 19 from the source 85 16, and wet steam or a suitable fluid at a lower temperature by a pipe 20 from the source 17, it being understood that the use of the word "steam" includes steam or other fluid used for this purpose. The valve gear 90 18 is controlled by an electric system having terminals in a mercury tube 21 connected to a bulb in the pipe 22 which leads the mixed wet and superheated steam to the coil 15. The electric terminals are connected to a 95 motor 24 forming part of the valve gear 18.

The steam from the vapor heating element or elements, to be later described, which operate in connection with the still 3, is led to the pipe 22 and mingled with the steam 100 from the mixing valve apparatus or gear 18 at a point α between the valve gear 18 and the bulb 23 which communicates to the U-shaped tube 21 a pressure which is an index of the temperature of the steam in the pipe 105 22, and the valve gear 18 operates to admit just as much wet steam or just as much superheated steam, or just as much of both as is necessary with the steam coming through the pipe 25 to give the desired 110 temperature at the air bulb 23 and thermal condition in the still 3. However, the exact arrangement of steam pipe described is not essential to the invention and the steam from the vapor heating element may be disposed of in any convenient manner within 115 the scope of the invention, the lay-out suggested being a good one but not essential as to its details to the successful utilization of the broad principles of the invention. Further, 120 the coils shown may be substituted by any convenient means for bringing the steam in heat-exchanging relation with the oil or oil vapor.

From the coil 15, the steam is led to a 125 pipe 30 which feeds the coil 14 in the still 2. This pipe 30 connects the valve gear 31, corresponding to the valve gear 18, or the pipes controlled thereby, with the coil 14, the pipe 32 from the coil 15 entering this 130

pipe at a point y between the valve gear 31 where the supplies of superheated and wet steam are controlled and mixed, and an air bulb 33 corresponding to the air bulb 23. 5 The pipe 32 is connected by a by-pass 35 around the still 2 with the pipe 40 leading from the valve gear 41 to the still 1 so that this steam may be utilized even if still 2 has to be cut out; and this pipe is controlled 10 by three-way valve 36. In the form of the invention shown, the steam from the vapor heating coil or coils in connection with the still 2 is also introduced into the pipe 30 between the valve gear and the air bulb 15 entering by way of a pipe 34 so that the steam from the heating coil 15 of the still 3 and steam from the vapor heating coil or coils to be described, which act on the vapors from the still 2, is in the lay-out shown 20 utilized in the coil 14 of the still 2. As the entire supply of steam admitted to the coil 14 passes in contact with the bulb 33, the temperature of this steam is, within the limits of its effectiveness on the oil and 25 down to the temperature of steam supply 17, entirely controlled by the return valve gear 31.

As the lay-out for supplying steam to coil 13 of still 1 bears practically the same relation to the means for supplying steam to the coil 14 of the still 2, and this may be equally true of all the stills which may be added, very little description of the connection to the other still or stills is necessary 35. There is a valve gear 41 corresponding to the valve gear 31, a pipe 40 leading steam from the valve gear 41 to the coil 13, a pipe 42 leading the steam which is passed through the coil 14 into the pipe 40 at a point z 40 between the air bulb 43 and the valve gear 41, and also a pipe 44 leading steam from the coil or coils which act on the vapor from the still 1, the pipe 44 as well as the pipe 42 joining the pipe 40 between the 45 valve gear 41 and the air bulb 43.

In connection with each still 1, 2, 3, I have shown a stillhead or vapor chamber 51, 52, 53. Referring to the stillhead or vapor chamber 53, I have shown therein a coil 54, though it is clearly within the scope of my invention to use one, two or more coils at the same or different temperatures, or other type of heat transfer devices for receiving steam, the mere multiplication of 55 these units being an obvious expedient in view of the present disclosure and easily arranged by anyone skilled in the art. This coil is supplied with steam by way of a pipe 55 from a mixing device or electrically operated valve gear 56 which receives steam by a pipe 57 from the wet steam supply 17 and steam by way of a pipe 58 from the superheated steam supply 16. This valve gear as shown is of the type described in 60 my Patent No. 933,577. There is a similar provision of coils and controls for each still-head. The coils are in the path of the vapors passing from the still and may be used either to raise their temperature and complete the cracking, or to lower their 70 temperature and condense the uncracked vapors, or there may be a plurality of coils of varying temperatures for both purposes. Any suitable means may be used for condensing the product. As shown, a pipe leads 75 from the dome or outlet of the still head at 580 to any suitable condensing apparatus 70 which may be identical for the different stills. In connection with the condenser, or each condenser, I use a pressure regulator 71 connected to the tank 72 which receives the 80 gases as well as the liquid from the condenser 70. This regulator determines the pressure at which the uncondensed gases pass to the furnace or gasometer regulating 85 the pressure in the entire system. This is an important feature as this is distinctly a system of cracking under pressure and dependent for its useful operation on a comparatively high and preferably regulated 90 pressure in the stills.

Each dome or stillhead contains an air bulb 59 connected to a U-shaped mercury tube 60 containing electric terminals connected to the motor 61 of the valve gear 56 95 so that the variation in temperature of the gas and vapors passing from the stillhead controls the operation of the motor and the temperature of the steam in the coil. Each stillhead is provided with a similar or equivalent apparatus with one or more coils which may be separately or collectively controlled, and in the form of layout shown, the steam from each of these coils is led into the steam supply of the heating apparatus of the corresponding still, though this arrangement may be varied within the scope of the invention. 100

In operation the oil which is to be cracked is introduced into the still at one end of the 110 series, as to the still marked 1, preferably entering at the bottom through the pipe 6 and comes first in contact with the bottom of the coil 13. In the still 1, the oil flow is upward in contact with the coil 13 which is 115 fed from the top and the oil overflows from the top through the pipe 4 into the bottom of the still 2 coming in contact there with the bottom portion of the coil 14. In this still, it likewise passes upward being drawn off at the top through the pipe 5 coming in contact with portions of the coil 14 at increasing temperatures as it passes upward, the coil 14 being fed from the top as is the coil 13 in the still 1. In the still 2, the oil 120 overflowing through pipe 5 passes into the bottom of the still 3 where the coil arrangement and path of the oil are similar to the same features in the previous stills. 125

In the still 3, the highly heated residue 130

from which all the constituents available for the manufacture of gasoline or the like, including gas and the lighter oils, have been evaporated after passing upward over the 5 coil 15, overflows through the pipe 7 and passes into the outlet or waste pipe 8. Each still 1, 2, 3 has a stillhead or vapor chamber 51, 52, 53 wherein the vapors are controlled as to their temperature by temperature regulating units 54 shown in the form of steam 10 coils and the temperature of each coil in each stillhead, as well as the temperature of each coil in each still, is regulated by a separate thermostatic element though where less 15 flexible adjustment is required, as when the desired temperatures of the different heating elements have a constant relation, the thermostatic control may be differently arranged and the different elements grouped 20 so as to reduce the number of thermostats. This apparatus is adapted to treat the heavier oils by subjecting them successively to predetermined temperatures, preferably heating the oil in one still to a certain temperature at which certain constituents are 25 evaporated or cracked or both, controlling the temperature of the vapors that come off from this still as indicated, heating to complete cracking if necessary, or cooling to 30 separate the vapors of the uncracked oils, then passing the oil to another still, heating it to a different, usually a higher temperature, subjecting the vapors from that still to the temperature or temperatures best 35 suited to producing the highest percentage of volatile liquid or liquid resembling gasoline and passing the residue to another still where it is heated to a still higher temperature for further cracking. The vapors from 40 each still are, in the apparatus shown, separately controlled as to their temperature for the purpose already recited so that as the oil passes from still to still, more and more of the crackable oils, or oils available for the 45 production of gasoline, are evaporated and the vapors heated at the desired temperatures. However, it is within the broad scope of my invention to pass all the vapors and gases to a single chamber or passage-way. 50 In the preferred and most economical arrangement of the apparatus, the lower end of the coil in still 1 with which the oil comes first in contact contains steam or water 55 condensed from the steam which has passed through the system, the temperature of the steam having been reduced as it passes through the system, transferring its heat to the oil in the still. In this way all the heat or practically all of it, with the 60 exception of what radiates from the pipes and from the outside of the tanks or stills, may be utilized, that is the steam from each of the coils in the vapor chambers or stills having been turned into and mingled with 65 the steam in the coils in the stills proper, is utilized for heating the oil, the coil of each still in turn being run into the next one. With the heating effect automatically controlled for each coil or temperature controlling unit in the entire system, practically no 70 heat is wasted. The steam or hot water, or both, passing from still 1 can evidently be utilized in various well-known ways for general plant purposes, or reheated for another series of stills. 75 I have thus described my invention specifically and in detail in order that its nature and operation may be fully understood; however, the specific terms herein are used descriptively rather than in their 80 limiting sense and the scope of the invention is defined in the claims:

1. In an apparatus for cracking oils, a plurality of stills for the oil, a heating unit submerged in the oil in each still, two sources of fluid under different thermal conditions, means for supplying fluid from each source to the heating units, thermostatically controlled means for each still operating independently of the other stills for regulating the supply of fluid from each source, a vapor chamber for each still, fluid operated means for heating the vapor in the chamber, means for supplying the fluid from the above-mentioned two sources, and a thermostat controlled by the temperature in the vapor chamber for controlling the supply of fluid from each said source and determining the fluid flow to the heater. 90

2. In an apparatus for cracking oils, a plurality of stills for the oil, a heating unit submerged in the oil in each still, two sources of fluid under different thermal conditions, means for supplying fluid from each source to the heating units, and thermostatically controlled means for regulating the supply of fluid from each source to each heating unit, with means for passing the fluid from the heating unit of one still to the heating unit in the next still, the thermostatically controlled fluid supply to each still after the first being mingled with that from the preceding still, and the thermostat being so placed as to be acted upon and controlled by the thermal condition of the 105 combined supply of fluid from all the various sources. 110

3. In an apparatus for cracking oils, a plurality of stills for the oil, a heating unit submerged in each still, two sources of fluid under different thermal conditions, means for supplying fluid from each source to the heating units, and thermostatically controlled means for regulating the supply of fluid from each source to each heating unit, 120 with means for passing the fluid from the heating unit of one still to the heating unit of the next still, the thermostatically controlled supply to each still after the first being mingled with that from the preceding 125 130

still, and the thermostat being acted upon and controlled by the thermal condition of the combined supply of fluid from all the various sources, the oil being passed through 5 the system from still to still in the opposite direction from the fluid flow.

4. In an apparatus for cracking oils, a plurality of stills for the oil, a heating unit submerged in each still, two sources of fluid 10 under different thermal conditions, means for supplying fluid from each source to the heating units, and thermostatically controlled means for regulating the supply of fluid from each source to each heating unit, 15 with means for passing the fluid from the heating unit of one still to the heating unit of the next still, the thermostatically controlled supply to each still after the first being mingled with that from the preceding 20 still, the oil being passed through the system from still to still in the opposite direction from the fluid flow.

5. In an apparatus for cracking oils, a plurality of stills for the oil, a fluid heating unit in each still, two sources of fluid under different thermal conditions, means for supplying fluid from each source to each of a plurality of the heating units, thermostatically controlled means for regulating 30 the supply of fluid from each source to each heating unit, with means for passing the fluid from the heating unit of one still to the heating unit of the next still, the thermostatically controlled supply to each still 35 after the first being mingled with that from the preceding still, and the thermostat being acted upon and controlled by the thermal condition of the combined supply of fluid from all the various sources, and means 40 for passing the oil through the system from still to still in the opposite direction to the fluid flow so that the low temperature oil entering the still comes in contact with the fluid about to leave the still and serves to 45 finally reduce its temperature, and as the oil advances from each still and from still to still, it is heated to a higher and higher temperature coming in contact with heating units of correspondingly higher temperatures, vaporizing the more easily and 50 then the more difficultly vaporized oils until all the material available for the production of gasoline and the like is removed.

6. In an apparatus for cracking oils, a 55 plurality of stills for the oil, a fluid heating unit in each still, two sources of fluid under different thermal conditions, means for supplying fluid from each source to each of a plurality of heating units, thermostatically 60 controlled means for regulating the supply of steam from each source to each heating unit, with means for passing the fluid from the heating unit of one still to the heating unit of the next still, means for passing the 65 oil through the system from still to still in

the opposite direction from the fluid flow so that the low temperature oil entering the still comes in contact with the fluid about to leave the still and serves to finally reduce its temperature, and as the oil advances 70 through each still and from still to still, it is heated to a higher and higher temperature vaporizing the more easily and then the more difficultly vaporized oils until all the material available for the production of 75 gasoline and the like is removed, and means for treating the vapor from each still at controlled temperatures whereby the largest percentage of product of nearly uniform volatility is obtained. 80

7. In an apparatus for cracking oils, a plurality of stills for the oil, a fluid heating unit in each still, two sources of fluid under different thermal conditions, means for supplying fluid from each source to each of a 85 plurality of heating units, thermostatically controlled means for regulating the supply of fluid from each source to each heating unit, with means for passing the fluid from the heating unit of one still to the heating 90 unit of the next still, means for passing the oil through the system from still to still in the opposite direction from the fluid flow so that the low temperature oil entering the still comes in contact with the steam about 95 to leave the still and serves to finally reduce its temperature, and as the oil advances from each still and from still to still, it is heated to a higher and higher temperature vaporizing the more easily and then the more 100 difficultly vaporized oils until all the material available for the production of gasoline and the like is removed, means for treating the vapor from each still at controlled temperatures whereby the largest percentage of 105 product of nearly uniform volatility is obtained, said means being in the form of fluid heating units with means for supplying fluid to the heating units from two sources under different thermal conditions 110 and thermostatically controlled means for regulating the flow from each source and determining the temperature at which the vapor is heated.

8. In an apparatus for cracking oils, a 115 plurality of stills for the oil, a fluid heating unit in each still, two sources of fluid under different thermal conditions, means for supplying fluid from each source to each of a plurality of heating units, thermostatically 120 controlled means for regulating the supply of fluid from each source to each heating unit, with means for passing the fluid from the heating unit of one still to the heating unit of the next still, means for passing the oil through the system from still to still in the opposite direction to the fluid flow so that the low temperature oil entering the still comes in contact with the fluid about to leave the still and serves to finally 125 130

reduce its temperature, and as the oil advances from each still and from still to still, it is heated to a higher and higher temperature vaporizing the more easily and then 5 the more difficultly vaporized oils until all the material available for the production of gasoline and the like is removed, means for treating the vapor from each still at controlled temperatures whereby the largest 10 percentage of product of nearly uniform volatility is obtained, said means being in the form of fluid heating units with means for supplying fluid to the heating units from two sources under different thermal conditions 15 and thermostatically controlled means for regulating the flow from each source and determining the temperature at which the vapor is heated, and means for returning the fluid from each vapor heating unit to 20 the system whereby it is utilized for further heating the oils.

9. In an apparatus for cracking oils, a plurality of stills for the oil, a fluid heating unit in each still, two sources of fluid 25 under different thermal conditions, means for supplying fluid from each source to each of a plurality of the heating units, thermostatically controlled means for regulating the supply of fluid from each source to each 30 heating unit, with means for passing the fluid from the heating unit of one still to the heating unit of the next still, the thermostatically controlled supply to each still after the first being mingled with that

from the preceding still, and the thermostat being acted upon and controlled by the thermal condition of the combined supply of fluid from all the various sources, means for passing the oil through the system from still to still in the opposite direction 40 from the fluid flow so that the low temperature oil entering the still comes in contact with the fluid about to leave the still and serves to finally reduce its temperature, and as the oil advances from each still and 45 from still to still, it is heated to a higher and higher temperature vaporizing the more easily and then the more difficultly vaporized oils until all the material available for the production of gasoline and the 50 like is removed, means for treating the vapor from each still at controlled temperatures whereby the largest percentage of product of nearly uniform volatility is obtained, said means being in the form of fluid heating units with means for supplying fluid to the heating units from two sources under different thermal conditions, and thermostatically controlled means for regulating the flow from each source and determining 55 the temperature at which the vapor is heated.

Signed by me at Baltimore, Maryland, this 23rd day of April, 1917.
